UNITED STATES PATENT OFFICE.

ALFRED COHN, OF MILWAUKEE, WISCONSIN.

DESIGN FOR A KNITTED SWEATER.

Application filed August 27, 1925. Serial No. 14,614. Term of patent 3½ years.

To all whom it may concern:

Be it known that I, ALFRED COHN, a citizen of the United States, residing at Milwaukee, in the county of Milwaukee and State of Wisconsin, have invented a new, original, and ornamental Design for Knitted Sweaters, of which the following is a specification, reference being had to the accompanying drawing, forming a part thereof.

The figure is a front elevation of a knitted sweater showing my new design. The lines on the drawing show the direction of stitching and also illustrate contrasting

effects produced by the use of different colors. The stitching is illustrated as being in horizontal rows through the arm and shoulder portions of the garment and in vertical rows through the lower body portions of the garment. A band of color corresponding to that used in the body of the garment crosses the horizontal rows of stitching in the shoulder portion.

I claim:—

The ornamental design for a knitted sweater as shown and described.

ALFRED COHN.
